By Nissen & Crane Atty.

UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

LINE LOCK FOR TYPEWRITERS.

Application filed April 28, 1924. Serial No. 709,328.

This invention relates to means for locking the operating mechanism of a typewriter against movement at a predetermined point in the travel of the carriage, as for instance at the end of the line, and has for its object the provision of such a device which shall be of improved construction and operation and which will be applicable to both power and hand-operated machines.

10 The invention is exemplified in the combination and arrangement of parts shown in the accompanying drawings and described in the following specification, and it is more particularly pointed out in the appended claims.

In the drawings:

Figure 1 is a somewhat fragmentary vertical sectional view of a typewriting machine showing one embodiment of the present invention.

Fig. 2 is a horizontal sectional view substantially on line 2—2 of Fig. 1.

Fig. 3 is a vertical sectional view substantially on line 3—3 of Fig. 2.

25 Fig. 4 is a fragmentary vertical section substantially on line 4—4 of Fig. 3.

The invention is illustrated in the drawing as applied to a Woodstock typewriting machine similar to that shown in my prior Patent 1,307,051, granted June 17, 1919. The numeral 10 designates the base frame of the machine having key levers 11 pivoted at 12 thereon and having a stop bar 13 secured to the rear of the carriage. The bar 13 is provided with adjustable stops 14, one of which is arranged to engage a pin 15 on a lever 16 as the carriage approaches the end of the line. The stop 14 may be adjusted to any desired position on the bar 13.

40 A link 17 connects the lever 16 with a bell crank 18, the bell crank being connected to a link 19 extending toward the front of the machine. The link and lever mechanism, together with the stop bar and stop, are similar to that in my prior patent referred to above. A power roller 20 may be employed for operating the type bars, the mechanism for this purpose being similar to that of my copending application, Serial

50 No. 703,927, filed April 3, 1925.

The forward end of the link 19 is provided with an upwardly extending bar or arm 21 having an angular slot 22 in its upper end, the slot being best shown in Fig. 4. A detent 23 is pivoted at 24 on the frame 10, and is provided with a spring 25, for normally rotating it in a counter-clockwise direction, as viewed in Fig. 1. The detent 23 is provided with a horizontally extending arm 26, which projects across one or more of the key levers 11 and is bent downwardly to carry a plate 27 positioned adjacent the lateral face of one of the levers 11. The rotation of the detent 23 under the influence of the spring 25 is limited by the stop member 28. A slotted bar or comb 29 extends across the frame of the machine to guide the key levers and to provide interlocking means to prevent operation of more than a single key lever at one time. The bar 29 carries a series of disks or tumblers 30 held in a groove therein by a plate 31. These disks have sufficient play longitudinally of the groove to permit depression of but a single key lever at one time. The downwardly depending plate 27 arranged adjacent one of the key levers, as shown more clearly in Fig. 3, will pass between two of the disks 30 and so take up the lost motion or play between the disks. When the plate 27 is thus depressed, the disks 30 will prevent depression of any one of the key levers, so that the key levers will be locked against operation. Depression of the plate 27 is effected by means of a pin 31 carried by an ear 32 formed on the detent 23. The pin 31 normally engages the vertical portion of the slot 22, so that the detent 23 will be rocked in a clockwise direction as viewed in Fig. 1, whenever the stop 14 engages the lever 16 to move the link 19 forwardly. It will thus be seen that at the end of the line, or at any other desired point in the travel of the carriage, as determined by the position of the stop 14, the key levers will be locked against movement through the action of the plate 27 on the interlocking disks 30.

It is frequently desirable to release the line-lock to permit the insertion of one or more letters in the line after the action of 100

the lock. For this purpose a release key 35 is pivoted at 36 to the machine frame, and is provided with a downwardly extending arm 37, having a laterally bent lug 38 underlying the link 19. A spring 39 connects the lug 38 with a laterally bent lug 40 on the end of the link 19. The spring 39 thus holds the release key 35 in its upward position, and at the same time draws the link 19 rearwardly. Depression of the release key 35 will lift the link 19 and the arm 21 upwardly so as to bring the horizontal portion of the slot 22 in registration with the pin 31. This will permit the spring 25 to rotate the detent 23 backwardly and lift the plate 27 out of contact with the disks 30, thus releasing the lock and permitting further operation of the key levers. As soon as the carriage is moved by a key lever operation to clear the pin 15 from the stop 14, the link 19 will move rearwardly, bringing the forward portion of the horizontal arm of the slot 22 into registration with the pin 31, so that the arm 21 can move downwardly bringing the pin 31 and slot 22 into the relation shown in Fig. 4, thus permitting the parts to resume their normal relation. It will be seen that the form of lock included in the present invention is especially useful in connection with a power-actuated machine, since it intercepts the movement of the key levers and prevents actuation of the power-driven parts. It is apparent that it would be impractical to attempt to lock the parts of the machine actuated by power while permitting movement of the key levers so as to connect the actuated parts with the source of power.

I claim:

1. The combination with a typewriting machine having a plurality of key levers, of a carriage; a stop movable with the carriage, interlocking means for preventing operation of more than a single key lever at one time, and means controlled by said stop at a predetermined position in the travel of said carriage for setting said interlocking means for preventing actuation of all said key levers.
2. In a typewriting machine, a plurality of key levers, movable tumblers interposed in the path of said key levers and having sufficient clearance for permitting actuation of a single key lever, and line-lock mechanism for taking up the clearance of said tumblers to prevent operation of said key levers.
3. In a typewriting machine, a plurality of key levers, a slotted comb for guiding said key levers, tumblers carried by said comb for preventing operation of more than a single key lever at one time, and means for locking said tumblers against movement at a predetermined point in the line to lock all of said key levers against operation.

4. The combination with a plurality of key levers, of interlocking means for preventing operation of more than one of said key levers at a given time, line-lock mechanism for setting said interlocking means in position to prevent operation of said key levers, and means for releasing said interlocking means to permit further operation of said key levers.

5. In a typewriting machine, a plurality of key levers, a plurality of tumblers interposed in the path of said key levers, a movable detent, and line-lock mechanism for moving said detent into and out of engagement with said tumblers to cause said tumblers to lock said key levers against operation.

6. A typewriting machine having a plurality of key levers, of interlocking means for preventing operation of a plurality of key levers at one time, a movable member for setting said interlocking means for preventing operation of all of said key levers, a carriage controlled member having a pin and slot connection with said movable member, said pin and slot connection being shiftable to permit release of said interlocking means.

7. In a typewriting machine having a plurality of key levers, of interlocking means for preventing operation of more than one key lever at a time, a movable detent for holding said interlocking means in position to prevent operation of all of said key levers, a member for actuating said detent, carriage-controlled means for actuating said member, and a release key for relatively moving said member and detent to permit release of said detent.

8. In a typewriting machine, a plurality of key levers, tumblers arranged in the path of said key levers for preventing operation of more than one key lever at a time, a detent having a locking device movable into and out of the path of said tumblers to lock said tumblers in position to prevent operation of all of said key levers, a carriage-controlled device for moving said detent having a pin and slot connection with said detent, and a release key for shifting said pin and slot connection to permit release of said detent when actuated by said carriage controlled device.

9. In a typewriter, a plurality of key levers, a slotted comb having a plurality of tumblers arranged in the path of said key levers and movable relatively to one another to permit operation of a single key lever at one time, and a line-lock detent positioned adjacent one of said key levers and movable into contact with said tumblers to hold said tumblers against movement and prevent operation of said key levers.

10. In a typewriting machine, a plurality

of key levers, movable tumblers for preventing operation of more than one key lever at a time, and a pivotally mounted detent having a horizontal extending arm arranged above said key levers, said arm carrying a downwardly extending plate adjacent one of said key levers and movable into engage-

ment with said tumblers to lock said tumblers and prevent operation of said key levers. ¹⁰

In testimony whereof I have signed my name to this specification on this 24th day of April, A. D. 1924.

OTTO A. HOKANSON.
